GEORGE NEILSON, OF BOSTON, MASSACHUSETTS.

Letters Patent No. 72,219, dated December 17, 1867.

IMPROVEMENT IN LAMPS.

The Schedule referred to in these Letters Patent and making part of the same.

TO WHOM IT MAY CONCERN:

Be it known that I, GEORGE NEILSON, of Boston, in the county of Suffolk, and State of Massachusetts, have invented certain new and useful Improvements in Lamp-Burners; and I hereby declare the following to be a full, clear, and exact description of the same, reference being had to the accompanying drawings, in which—

Figure 1 represents an elevation,

Figure 2 a vertical central section, and

Figure 3 a plan view of a burner constructed in accordance with my invention.

My invention relates to that class of burners for hydrocarbon fluids, in which the open dome or deflector is elevated some distance above the base of the burner, so as to allow the light to pass out from above and below said deflector, and so as to prevent the lower part of the chimney, which extends outside of and below the dome, from becoming heated.

My invention consists principally of, first, the combination with an annular disk or plate, elevated upon suitable supports, so as to encircle the upper part of the wick-tube, of a deflector or dome, hinged to said plate, in the manner hereinafter described; second, the combination, with the annular dome-supporting plate, of a ring of leather, or other non-conductor of heat, secured upon the periphery of such plate, so as to prevent the heat of the dome or plate from being communicated to the chimney which encircles and is supported by said plate; third, a base or chimney-rest, having a frusto-conical shape, and provided with a series of radial corrugations, which, when the chimney is in place, constitute the air-spaces through which the external air passes into the interior of the burner; fourth, the combination of the hinged dome and its annular supporting-plate with the radially corrugated base or chimney-rest.

To enable those skilled in the art to understand and use my invention, I will now proceed to describe the manner in which the same is or may be carried into effect, by reference to the accompanying drawings.

The cylindrical lower part *a* of the burner, which receives and supports the wick-tube, is of ordinary or suitable construction. Around the upper-end of the part *a* is secured a metal plate, *b*, of frusto-conical shape, as shown in fig. 2, having formed in it a series of radial corrugations, *c*. This plate forms the base or rest for the chimney, as will be hereinafter explained. The wick-tube *d* extends up some distance above the base *b*, as is usual in this species of burner, and over its upper end is placed the dome or deflector *f*. The deflector rests on an annular disk, *h*, which is supported in position above the base *b*, by means of wires, or other suitable supports, *i*, whose lower ends are soldered or otherwise suitably attached to the base. Under this arrangement the space between the disk and base is entirely open, allowing the external air to circulate freely between them.

The cone or deflector is of ordinary construction, being provided with the usual perforations, *k*, to allow the necessary supply of air to pass into that part of the chimney above the deflector. In order, however, to secure the cone in proper position upon its supporting-disk, and at the same time to admit of its being removed or turned back, so as to uncover the wick-tube, I provide the dome, at any point upon the periphery of its base, with a short arm, *l*, which projects downwards at about right angles to the base, and passes through a slot, *m*, of suitable size, formed for its reception in the disk *h*. There is thus a hinge-joint formed, which admits of the cone being turned back from the wick-tube whenever occasion requires. The position of the arm *l*, when the cone is over the tube, is shown in fig. 2, and in black lines, fig. 1. When it is desired to uncover *l*, when the cone is over the tube, is shown in fig. 2, and in black lines, fig. 1. When it is desired to uncover *l*, the wick-tube, the cone is lifted or tilted back, until it assumes the position shown in red lines, fig. 1. The arm *l* now rests against the under side of the disk *h*, and prevents the cone from being swung further back.

It will also be noticed that the nature of the joint admits of the dome being lifted away from the disk whenever desired, the arm slipping easily out of the slot *m*. The chimney *n* is of such size as to fit over or around the disk *h*, and when placed in proper position on the burner, its lower end rests on or is supported by the corrugated base or chimney-rest *b*, as shown in the drawings. In order to keep the chimney from contact with the cone-supporting disk, as well as to support and steady it, I attach upon the periphery of the disk a ring or strip of leather, *p*, or other suitable non-conductor of heat. By this means the disk and cone are prevented from communicating heat to the chimney, thus keeping the lower part of the chimney much cooler than

in ordinary burners of this kind. The ring can be made of rubber, cloth, or any other suitable material, and its flexible or yielding nature admits of its conforming to the shape of the chimney so as to hold the latter firmly in place. It may be attached to the disk by any ordinary or suitable means. I prefer, however, the method shown in the drawings; slits being made in the edge of the disk, so as to form a series of arms, *s*. The leather ring is held by these arms, passing above and below the arms alternately, as shown plainly in the drawings.

While preferring to connect the dome and its disk in the manner above explained, it will, of course, be evident that any ordinary or suitable hinge-joint or connection may be used for the same purpose, though not with equally good results, and I therefore do not limit myself to the precise joint herein described, but contemplate employing any other suitable hinge connection. When the chimney is in the position indicated in red lines, fig. 1, the external air is free to pass under its base through the openings formed by the corrugations in the chimney-rest *b*. This continuous current of air tends, of course, to reduce the heat of the lower part of the chimney, and as by means of the non-conducting ring *p* the cone and disk are prevented from communicating their heat to the chimney, the lower part of the chimney is kept cool and almost entirely free from heat. There is, therefore, little or no liability of the chimney being broken or cracked by the heat, a defect which is noticeable in all burners of this kind heretofore made.

Having now described my invention, and the manner in which the same is or may be carried into effect, what I claim, and desire to secure by Letters Patent, is—

1. The combination, in a burner such as described, with the elevated dome-supporting disk, of a dome or deflector, hinged to said disk, substantially as and for the purposes set forth.
2. The combination, with the dome or deflector and the arm projecting from its base, of the dome-supporting disk, and slot formed in the same for receiving and holding said arm, substantially in the manner and for the purposes set forth.
3. The combination, with the dome-supporting disk, of a ring of leather or other suitable material, which is a non-conductor of heat, secured upon the periphery of said disk, substantially as and for the purposes set forth.
4. The base or chimney-rest, constructed substantially as herein described, that is to say, provided with a series of radial corrugations, which, when the chimney is in place, allow the external air to pass into the burner between the base of the chimney and the said rest, substantially as set forth.
5. The combination of the radially corrugated base or chimney-rest, with the dome-supporting disk, and dome or deflector hinged to said disk, under the arrangement and for operation as set forth.

In testimony whereof, I have signed my name to this specification before two subscribing witnesses.
